Strehli & Hill

UNITED STATES PATENT OFFICE.

JOHN O. HIBBARD, OF HARTWELL, OHIO.

MUSTACHE-PROTECTOR.

SPECIFICATION forming part of Letters Patent No. 408,013, dated July 30, 1889.

Application filed November 15, 1888. Serial No. 290,885. (No model.)

To all whom it may concern:

Be it known that I, JOHN O. HIBBARD, (having made oath of my intention to become a citizen of the United States,) a resident of 5 Hartwell, in the county of Hamilton, State of Ohio, have invented certain new and useful Improvements in Mustache-Protectors, of which the following is a specification.

The object of my invention is to provide a 10 separable mustache-protector which shall be self-adjusting to fit varying diameters and thicknesses of drinking-vessels.

In the drawings accompanying this specification and forming a part thereof, Figure 1 15 is a top view of my improved mustache-protector as applied to a large-sized drinking-vessel. Fig. 2 is a view in elevation of the top portion of the cup shown in Fig. 1, with the protector attached, the dotted lines showing 20 the position of the central plate-flanges. Fig. 3 is a bottom view of the protector removed from the vessel, showing the relative positions of the different parts when applied to a large drinking-vessel, such as shown in 25 Figs. 1 and 2, and the preferable form of spring mechanism for adjusting the same. Fig. 4 is a top view of the central plate, showing the preferable form of circular slots 30 therein to admit of adjustment to vessels of varying diameters and thicknesses, as will more fully hereinafter appear. Fig. 5 is a top 35 view, on a smaller scale, of a vessel provided with the mustache-protector, showing the relative position of the two end clamp-plates when applied to such a vessel.

As preferably constructed, my invention consists of a central plate A and two end clamp-plates B B. To each of the plates B is riveted a lug a, which will admit of said plate 40 being rotated thereon; which lug is adapted to enter the slot b in the plate A through the enlarged portion thereof, as shown in Fig. 3.

The central plate A is preferably provided at each end, for a part only of its circumference, with the upturned flanges b', in which 45 are made suitable cuts b², in which one end of each spring D is secured, the other end of said springs being bent to fit the configuration of the lugs a, attached to the clamp-plates B, as

shown in Fig. 3. One end of each spring being connected to the plate A and the other end of said springs being connected to the lugs a, attached to the clamp-plates B, the tendency is to continually draw said plates inward through the medium of said spring- 55 connection and clamp the vessel between the flanges of said clamp-plates and the central plate.

The circular-shaped slots in the plate A and the pivotal connection between the plates B B 60 and lugs a will admit of the mustache-protector being applied to vessels of varying diameters and thicknesses. Any operative form of spring-connection between the central plate A and lugs a may be employed. 65

The central plate A and the clamp-plates B B are preferably made of German silver, but may be made of any other suitable material— 70 as, for example, papier-maché, celluloid, &c.

The ends of the plate A not being a true circle and the clamp-plates being pivotally connected to lugs a admit of the vessel being clamped between the outer flange b³ of the clamp-plates B and that portion of flange b' next the mouth-opening of the central plate 75 A, thus preventing the liquid from flowing between said flanges.

The advantages of my improved mustache-protector are apparent. It is ornamental and answers every purpose of the ordinary mustache-cup. It is especially valuable to traveling men, as it can be carried in the pocket without any inconvenience, and can be readily adjusted and applied to any ordinary-sized 80 drinking-vessel. The construction is such that no liquid can escape except through the mouth-opening. When it is desired to clean 85 the protector, all that is necessary to do is to disengage the springs from around the lugs, when the clamp-plates are free to be removed 90 from the central plate, the lugs passing through the enlarged portions of the slots.

What I claim as new, and desire to secure by Letters Patent, is—

1. A mustache-protector consisting of a central plate A, having circular slots b therein, and clamp-plates B B, having the lugs a pivotally connected thereto, said lugs projecting 95

through said slots b , and suitable spring-connection between said central plate and lugs a , substantially as set forth.

2. A mustache-protector consisting of a central plate A , having the circular slots b and upturned flanges b' , the latter having the slots b^2 cut therein, and the clamp-plates $B B$, having the lugs a pivotally connected thereto,

and downwardly-turned flanges b^3 and springs D , the latter being secured at one end in the slots b^2 and at the other end attached to the lugs a , substantially as set forth.

JOHN O. HIBBARD.

Attest:

H. H. JACKSON,
ED. STREHLI.
